GLENN H. CURTISS, DECEASED, LATE OF COUNTRY CLUB ESTATES, FLORIDA, BY LENNA P. CURTISS, EXECUTRIX, OF MIAMI SPRINGS, FLORIDA

DESIGN FOR A TOW CAR AND TRAILER COMBINATION

Application filed January 8, 1931. Serial No. 38,235. Term of patent 14 years.

To all whom it may concern:

Be it known that GLENN H. CURTISS, deceased, late a citizen of the United States, residing at Country Club Estates, in the county of Dade and State of Florida, did invent a new, original, and ornamental Design for Tow Car and Trailer Combination, of which the following is a specification, reference being had to the accompanying drawings, forming a part thereof, and in which:

Fig. 1 is a plan view of the tow car and trailer combination, and

Fig. 2 is a side elevation thereof.

The present design comprises as the principal and dominating features thereof the forward portion of a trailer body tapered to a

V-shaped prow, with a roof converging downwardly and laterally at its front end to merge with said V-shaped prow, and the underside of said V-shaped prow formed with an up-sweep concave curve joining at its upper forward end the approximate middle of a raised rearwardly rounded deck of an automobile tow car giving the appearance of a goose neck connection.

What is claimed is:

The ornamental design for a tow car and trailer combination, substantially as shown and described.
